UNITED STATES PATENT OFFICE.

RUFUS GOULD, OF NEW YORK, N. Y., ASSIGNOR OF ONE-HALF TO POSTAL TELEGRAPH-CABLE COMPANY, OF NEW YORK, N. Y., A CORPORATION OF CONNECTICUT.

ANCHOR ROD.

Application filed February 24, 1927. Serial No. 170,722.

My invention relates to anchor, guy or stress rods and pertains more particularly to improvements in that type of such devices which are chiefly used in providing guys and anchors for electrical communication or transmission lines.

The principal objects contemplated by my invention consist in providing an anchor rod of such nature, that the friction between the 10 rod and the strand used therewith is reduced in order that the tensioning of guys or anchors may be facilitated; that rubbing friction is eliminated between the strand and rod to prevent scoring and destruction of the 15 galvanized coating usually placed on such rods and strand; and that the strand is guided and constrained to a position which simplifies and expedites the clamping operation.

Anchor or stress rods as heretofore used 20 are provided with an eye in one extremity through which the strand is threaded. When an external force is placed on the free end of the strand and it is pulled through the eye in the operation of tensioning the guy 25 or anchor, the galvanized coating on the strand and on the inner surface of the eye is almost invariably stripped off, leaving the iron or steel surface unprotected and exposed and thus subject to rapid oxidization aggravated by electro-chemical action due to the 30 presence of the dissimilar metals, iron or steel and zinc. Further the necessity for manually holding the two lines of strand parallel to receive a clamp is difficult and 35 occasions delay.

In my improved device I provide a sheave 40 attached to the rod and strand guides, so located with respect to the sheave that as the tensioning force is placed on the strand the strand rotates the sheave to eliminate rubbing friction while the guides constrain the two lines of strand into the proper position to readily receive the clamp.

Other objects and uses will be apparent 45 from the following description and drawings in which like reference numerals designate corresponding parts throughout and in which:

Fig. 1 is a side elevation of one complete 50 embodiment of my device.

Fig. 2 is a plan view of the same with detachable clamp member removed.

Fig. 3 is an end view of the device as shown in Fig. 2.

Fig. 4 is a side elevation with clamp removed, and thimble or sheave in section.

Fig. 5 is a plan view of an alternative embodiment of my device with a portion of the strand broken away.

Fig. 6 is an end view of the device shown in Fig. 5 with the strand shown in section.

Fig. 7 is a side elevation of the device of Figs. 5 and 6.

The embodiment of my device illustrated in Figs. 1-4 inclusive comprises a rod 1, one extremity of which may be threaded and provided with a nut 2 as shown whereby the device may be attached to an anchor block or other support. The other extremity of the rod 1 is formed to have a flattened portion 3 in which are formed two parallel grooves 4 and 5, of substantially semi-circular cross-section. The longitudinal axes of the grooves are in one plane and are parallel to the longitudinal axis of the rod 1. A stud 14 is provided on the flattened portion of the rod and between the cylindrical portion of the rod and the guides 4 and 5. The axis of this stud is substantially perpendicular to and in the same plane as the longitudinal axis of the rod. The stud 14 carries a sheave or thimble 13 adapted to rotate thereon, and be retained thereby. The upper extremity of the stud is formed after the thimble is placed in position thereon, to have a retaining lip, as shown in Fig. 1. Fig. 4 illustrates the form of the upper extremity of the stud 14 before the retaining lip is formed. The guides 4 and 5 are so spaced with respect to each other and the diameter of the thimble 13 and are so located with respect to the normal plane of rotation of the thimble 13 that as the strand is tensioned the two lines of strand naturally fall into the grooves 4 and 5 and are constrained thereby into parallel relation to receive a detachable member 15 which is provided with parallel grooves similar to and spaced exactly the same as the grooves 4 and 5, and which when held in place by the bolts 6, 7 and 8 to the flattened portion 3 forms a clamp for the strand 12 to maintain the tension on the strand and rod. The strand is constrained by the guides 4 and 5, as hitherto mentioned, because the height of the stud 14 is such with respect to the plane of the axes of the guides 4 and 5 that this plane coincides with the plane in which the thimble is constrained to rotate, by the retaining lip

on the stud, when a tensioning force is placed on the strand.

The particular embodiment shown in Figs. 5 and 7 comprises a rod 21, one extremity of which is formed to provide a flattened and broadened portion 25 provided with a pair of oppositely disposed hooks, 26 and 27 of substantially semi-circular form. A stud 23 is located with its axis substantially perpendicular to and in the same plane as the longitudinal axis of the rod 21 and is located near the cylindrical portion of the rod and between that portion of the rod and the hooks 26 and 27. A thimble 24 is carried and retained by the stud 23 and is adapted to rotate thereon. Thus as the strand 28 is tensioned the thimble 24 rotates and thus eliminates rubbing friction between the strand and the rod, while the hooks 26 and 27 are so located with respect to each other and to the diameter of the thimble 24 as to guide and constrain the strand to form two parallel lines properly spaced to receive a separable clamp not shown in figures. The other extremity of the rod 21 is threaded and provided with a nut 22 whereby the rod may be attached to a suitable support.

It will be observed from the foregoing that my improved device eliminates rubbing friction, scoring or destruction of the galvanized coating of the strand and further simplifies, facilitates and expedites the installation of anchors or guys.

While I have illustrated and described two

embodiments of my device it should be 35 clearly understood that I may make numerous modifications in the details thereof without departing from the spirit or narrowing the scope of my invention.

What I claim is:—

1. An anchor rod, one extremity of which is formed to have a flattened portion, a stud carried by said flattened portion and located near the cylindrical portion of said rod with its axis substantially perpendicular to the longitudinal axis of said rod, a thimble carried and retained by said stud, strand guiding and constraining means provided in the flattened portion of said rod, and a detachable member adapted to be secured to said guiding means to form with said guiding means a strand clamp. 40 45 50

2. An anchor rod, a portion of one extremity of which is flattened and provided with a pair of parallel grooves the axes of which are in one plane and are parallel with the longitudinal axis of said rod, a stud located between the cylindrical portion of said rod and said grooves and with its axis perpendicular to and in the same plane as the longitudinal axis of said rod, a thimble carried and retained by said stud and adapted to rotate thereon with its axis of rotation normally in the plane of the axes of said grooves and a detachable member adapted to 55 60 65 be secured to that part of said flattened portion which bears said grooves.

RUFUS GOULD.
